UNITED STATES PATENT OFFICE.

ELTON R. AGNER, OF VINTON, VIRGINIA, ASSIGNOR OF ONE-HALF TO J. EMMETT GISH, OF ROANOKE, VIRGINIA.

TRACK OILER.

Application filed December 20, 1927. Serial No. 241,375.

This invention relates to track oilers and more particularly to a device of this kind operating to lubricate a rail comprised in a curved portion of a trackway.

5 It is also an object of the invention to provide a device of this kind comprising a wheel adapted to travel along the rail to be lubricated, said wheel constituting a container for the desired lubricant together with normally closed ports through which the lubricant is adapted to be discharged upon the rail.

10 The invention also has for an object to provide a device of this kind comprising a reservoir or supply member in the form of a wheel adapted to travel along the rail to be lubricated and which is provided in a wall with a plurality of ports, said ports being arranged to discharge upon a side face of the 15 ball or head of the rail together with valve members normally closing said ports but being moved into open position by contact with the rail.

20 An additional object of the invention is to provide an applicating member adapted to travel on the rail to be lubricated together with means operable at will for heating said applicating member.

25 Another object of the invention is to provide a device of this kind comprising an applicating member adapted to travel along a rail and to lubricate only the inside face of the ball or head of such rail, said applicating member being normally out of contact with the rail together with means operable at will 30 for moving said applicating member into desired engagement with the rail.

35 The invention consists in the details of construction and in the combination and arrangement of the several parts of my improved track oiler whereby certain important advantages are attained and the device rendered simpler, less expensive and otherwise more convenient and advantageous for 40 use, as will be hereinafter more fully set forth.

45 The novel features of my invention will hereinafter be definitely claimed.

In order that my invention may be the 50 better understood, I will now proceed to describe the same with reference to the accompanying drawings, wherein:—

Figure 1 is a view in side elevation with portions in section and of a somewhat dia-

grammatic character illustrating a rail oiler 55 constructed in accordance with an embodiment of my invention;

Figure 2 is a fragmentary view in top plan illustrating an applicating member and the parts directly associated therewith; 60

Figure 3 is an enlarged fragmentary view partly in section and partly in elevation of the applicating member and its associated parts as herein disclosed and in working engagement with the rail of a trackway; 65

Figure 4 is an elevational view of the means herein employed for maintaining normally closed the valves for the discharge ports of the applicating member.

As disclosed in the accompanying drawings, 1 denotes an axle comprised in a pony truck or kindred structure of a locomotive and with which is engaged for swinging movement in a vertical direction the forwardly directed parallel arms 2. These 70 arms 2 at their outer end portions are tied or connected by an upstanding yoke member or bail 3. The central portion of the yoke member or bail 3 has operatively engaged therewith an upstanding stem 4 which is 75 operatively connected, as at 5, with the extended portion of the rod 6 of a piston 7.

The piston 7 is arranged for reciprocation within a cylinder 8 suitably supported by the body of the locomotive L or kindred rolling 80 stock and the cylinder 8 has in communication therewith inwardly of the piston 7 the pipe line 9 leading from a source of fluid under pressure. Although not shown this line 9 at a point within ready access of an 85 engineman is adapted to have interposed therein a controlling valve so that when desired fluid pressure may be admitted within the cylinder 8 to force the piston 7 downwardly for a purpose to be hereinafter more 90 particularly referred to. The piston 7 is normally urged upwardly by an expansible member 10 of requisite tension and herein disclosed as a coil spring arranged within the cylinder 8 and interposed between the 95 piston 7 and the lower or bottom head of the cylinder 8.

The applicating member M comprises two sections 11 and 12 arranged side by side and which in their assembly constitute a hollow 100 structure adapted to contain a requisite supply of lubricant. The section 11 may be termed a "wheel section" and is provided

with a tread 14 adapted to have conventional rolling contact upon the rail R to be lubricated and also includes the inner flange 15 adapted to lap the inner side face or wall of the head or ball of the rail R when the section 11 is in rolling contact with the rail. The section 12, as herein disclosed, is substantially conical in form with its apex disposed in a direction away from the section 11. Both of the sections 11 and 12 at their axial centers have formed therewith the hub sleeves 16 which, when the sections 11 and 12 are assembled, have close contact one with the other. The hub sections 16 extend upwardly of the sections 11 and 12 and are rotatably engaged with the extremities of the yoke member or bail 3. Disposed through the aligned hub sleeves 16 is a holding bolt 17 having engaged with an end portion thereof a conventional nut 18 whereby the sections 11 and 12 are effectively maintained in desired relative assembly. The inclined peripheral wall of the section 12 at a desired point thereon is provided with a filling opening 19 normally closed by a plug 20.

The flange 15 of the section 12 at points equi-distantly spaced in a direction circumferentially of the section is provided with the discharge ports 21 which are normally closed by the ball valves 22. Each of the valves 22 in its normally closed position extends a slight distance outwardly beyond the outer face of the flange 15.

35 The ball valves 22 are maintained in their normally closed positions by a retaining member A comprising the central disc or plate 23 mounted upon the inner end portion of the hub sleeve 16 of the section 11 and herein disclosed as held thereon through the instrumentality of the holding nut 24. Radiating from the plate 23 are the spring arms 25 each of which having its outer extremity contacting with a ball valve 22 under sufficient tension to maintain said ball valve normally closed but permitting said ball valve to readily move inwardly to open position.

With the applicating member M in its normal or raised position the flange 15 thereof is positioned slightly inward of the inner side face or wall of the rail R or slightly offset outwardly with respect to the flange 26 of the pony truck wheel 27 or the like immediately to the rear thereof. When it is desired to oil or lubricate a rail, fluid under pressure is admitted within the cylinder 8 resulting in downward movement of the piston 7 which operates to swing the yoke member or bail 3 downwardly, thus causing the tread 14 of the applicating member M to have requisite rolling contact with the rail R. As the flange 15 laps the inner side face of the rail R and as the member M rotates, the ball valves 22 as they come into

contact with said inner face or wall of the rail will be moved inwardly into open position and at the same time caused to rotate while in contact with such face or wall. This results in requisite application of the 70 lubricant to the inner side face or wall of the rail only and at points spaced along such wall or face in accordance with the spacing of the ports 21. The rolling action of the valves 22 facilitates the desired delivery of 75 the lubricant.

In order to assure the proper engagement of the applicating member M with the rail R it is necessary that the member be capable of axial movement and for which 80 reason the outer or extended portions of the hub sleeves 16 are freely disposed through the end portions of the yoke member or bail 3. The member M is normally urged in an outward direction by an expansible member 85 28 of requisite tension and herein disclosed as a coil spring encircling the extended portion of the hub sleeve 16 of the section 12 of the member M and interposed between the adjacent end of the section 12 and an 90 end portion of the yoke member or bail 3. This expansible member or spring 28 serves to maintain the member M, when raised or inoperative, in the position with respect to the wheel 26 as particularly illustrated in 95 Figure 2 of the accompanying drawings and which has hereinbefore been referred to.

The lubricant employed may be as desired, preferably of an oil of desired consistency. Under certain conditions this oil 100 or lubricant may not flow or be delivered by the valve members 22 as freely as desired. For this reason there is disposed over the upper portion of the applicating member M a hood or casing 29 held in desired position 105 by the yoke member or bail 3. This hood or casing 29 while positioned in close proximity to the member M and closely conforming to its peripheral configuration is spaced therefrom sufficiently to offer no hindrance or 110 obstruction to the desired rotation of the member M. A steam line 30 leading from a suitable source of supply, such as an engine boiler, discharges within the space between the hood or casing 29 and the member 115 M resulting in sufficient heating of the member M to assure the oil maintaining a requisite flowing condition. This line 30 is adapted to have interposed therein a suitable controlling valve (not shown) easily accessible 120 by an engineman.

It is believed to be evident that a track oiler as hereinbefore set forth is of especial advantage in lubricating a rail particularly at a curve in the trackway and that such lubrication serves to increase the life of the rail together with the life of the wheel flange. Furthermore, efficient lubrication of the rail serves to decrease strains on the locomotive or kindred rolling stock due 130

to friction and lessens the liability of breakage of draw heads, and at the same time facilitates easy starting of trains and assures unlimited saving in time, fuel and 5 repairs.

From the foregoing description it is thought to be obvious that a track oiler constructed in accordance with my invention is particularly well adapted for use 10 by reason of the convenience and facility with which it may be assembled and operated, and it will also be obvious that my invention is susceptible of some change and modification without departing from the 15 principles and spirit thereof and for this reason I do not wish to be understood as limiting myself to the precise arrangement and formation of the several parts herein shown in carrying out my invention in 20 practice except as hereinafter claimed.

I claim:—

1. A rail oiler comprising a hollow applicating member adapted to contain a supply of lubricant, means for supporting said applicating member for movement toward or from the rail, said member when in contact with the rail having rotation, said applicating member having a flange lapsing a side face of the rail when the member is in rolling contact therewith, said flange being provided with a series of ports spaced circumferentially of the member, ball valves normally closing said ports and projecting outwardly beyond said flange when 30 in their normally closed position, and yielding means for maintaining the valves in their normal position.

2. A rail oiler comprising a hollow applicating member adapted to contain a supply of lubricant, means for supporting said applicating member for movement toward or from the rail, said member when in contact with the rail having rotation, said applicating member having a flange lapsing a side face of the rail when the member is in rolling contact therewith, said flange being provided with a series of ports spaced circumferentially of the member, ball valves normally closing said ports and projecting outwardly beyond said flange when in their 40 normally closed position, and a plate mounted within the applicating member and provided with spring arms contacting with the

ball valves for maintaining said valves in their normal positions. 55

3. A rail oiler comprising a hollow applicating member adapted to contain a supply of lubricant, means for supporting said applicating member for movement toward or from the rail, said member when in contact with the rail having rotation, said applicating member having a flange lapsing a side face of the rail when the member is in rolling contact therewith, said flange being provided with a series of ports spaced 60 circumferentially of the member, ball valves normally closing said ports and projecting outwardly beyond said flange when in their normally closed position, and means for urging the applicating member in the direction of its axis toward the rail when said applicating member is in rolling contact with the rail. 65

4. A rail oiler comprising a hollow applicating member adapted to contain a supply of lubricant, means for supporting said applicating member for movement toward or from the rail, said member when in contact with the rail having rotation, said applicating member having a flange lapsing a side face of the rail when the member is in rolling contact therewith, said flange being provided with a series of ports spaced 70 circumferentially of the member, and ball valves normally closing said ports and projecting outwardly beyond said flange when in their normally closed position. 75

5. A rail oiler comprising a hollow applicating member adapted to contain a supply of lubricant, means for supporting said applicating member for movement toward or from the rail, said member when in contact with the rail having rotation, said applicating member having a flange lapsing a side face of the rail when the member is in rolling contact therewith, said flange being provided with a series of ports spaced 80 circumferentially of the member, ball valves normally closing said ports and projecting outwardly beyond said flange when in their normally closed position. 85

In testimony whereof I hereunto affix my

signature.

ELTON R. AGNER.
